UNITED STATES PATENT OFFICE.

SAMUEL HOUSTON WARREN, OF HURRICANE, TENNESSEE.

RAILWAY-TIE.

No. 863,682.

Specification of Letters Patent.

Patented Aug. 20, 1907.

Application filed May 6, 1907. Serial No. 372,061.

To all whom it may concern:

Be it known that I, SAMUEL HOUSTON WARREN, a citizen of the United States, residing at Hurricane, in the county of Humphreys and State of Tennessee, have 5 invented certain new and useful Improvements in Railway-Ties, of which the following is a specification.

This invention is a railway tie and has for its object an improved metallic tie and means for securing the rails thereto.

10 In the accompanying drawing, Figure 1 is a side elevation of the tie. Fig. 2 is a plan view. Fig. 3 is a longitudinal section. Fig. 4 is a transverse section on the line 4—4 of Fig. 1. Fig. 5 is a transverse section on the line 5—5 of Fig. 1.

15 Referring specifically to the drawing, the tie, which is in the form of a channel-beam, with the channel downwardly presented, comprises a top 10, side walls 11 and end walls 12 closing the channel. In the top of the beam, at its ends, are recesses 13 to receive a tenon 20 on the bottom of rail-chairs 15, the recesses and tenons being shaped to form a dovetail joint. The chairs have integral rail-holding means indicated at 16 and 17, respectively, said means comprising flanges which engage the web and base flanges of the rails 18 25 in the manner of the ordinary fish-plates. The rail ends meet in the chair and are fastened therein by means of bolts 19 passing through the flanges 16 and into the rail webs. In the bottom of each recess 13 is a pocket 20 in which a spring 21 seats which engages 30 the bottom of the tenon 14 whereby the rail-chair is cushioned to lessen the shock and noise from the passage of a train over the joint. The spring is in vertical alinement with the rail.

In the end walls 12 of the tie is mounted a non-traveling screw 22 which is oppositely threaded, and on each of such threaded portions is mounted a nut 23 which fits snugly between the side walls 11 whereby it is prevented from turning when the screw is turned. Each nut carries a stem 24 which passes through a slot 25 in 40 the top of the tie, and through the respective rail-chairs. The stem is threaded to receive a fastening nut 26 engaging the top of the chair. By reason of the connec-

tion between the nut and the chair, the latter will be caused to travel with the former when the screw is turned. The chairs can therefore be readily adjusted 45 to maintain the proper gage upon turning the screw, and they will be securely held in adjusted position to prevent spreading of the rails. For convenience in operating the screws, the outer ends, which project from the end walls 12 of the tie, are squared to receive 50 a suitable tool for turning it.

At the top of the tie are outwardly projecting longitudinal flanges 27 to which the chairs are also made fast by means of bolts 28. The bolts pass through slots 29 in the flanges in order that the adjustment of the chair 55 heretofore referred to may be made.

I claim:—

1. The combination with a railway tie, of rail-chairs thereon, a non-traveling screw mounted in the tie, and nuts traveling on the screw and connected to the rail-chairs. 60

2. The combination with a railway tie recessed on top, of rail-chairs seating in the recess, a non-traveling screw mounted in the tie, and nuts traveling on the screw and connected to the rail-chairs. 65

3. The combination with a railway tie comprising a recessed top, and side and end walls, of rail-chairs seated in the recesses of the top, a non-traveling screw mounted in the end walls, and nuts traveling on the screw and connected to the rail-chairs. 70

4. The combination with a railway tie comprising a top provided with openings, and side and end walls, of rail-chairs on the tie, a non-traveling screw mounted in the end walls, nuts traveling on the screw, and stems carried by the nuts and passing through the openings in the top, and connected to the rail-chairs. 75

5. The combination with a railway tie comprising a top, and side and end walls, of rail-chairs on the tie, a non-traveling screw mounted in the end walls, nuts traveling on the screw and fitting between the side walls, and a connection between said nuts and the rail-chairs. 80

In testimony whereof I affix my signature, in presence of two witnesses.

his
SAMUEL HOUSTON X WARREN.
